[57] CLAIM

The ornamental design for a urine relief tube, as shown and described.

DESCRIPTION

FIG. 1 is a side view illustrating a urine relief tube showing my new design, the opposite side being a mirror image thereof;

FIG. 2 is a top plan view thereof;

FIG. 3 is a rear end view thereof;

FIG. 4 is a front end view thereof;

FIG. 5 is a bottom plan view thereof;

FIG. 6 is a perspective view thereof;

FIG. 7 is a perspective view illustrating the relief tube with top open and with the storage bag attachment ring removed; and,

FIG. 8 is a perspective view illustrating the relief tube with a storage bag secured between the attachment ring and neck of the tube.

The broken line showing of the environmental structure of a storage bag in FIGS. 7 and 8 is for illustrative purposes only and forms no part of the claimed design.
